(57) **CLAIM**

The ornamental design for a stand for portable electronic devices, as shown and described.

DESCRIPTION

FIG. 1 is a first perspective view of a stand for portable electronic devices showing my new design, illustrated in a first position;

FIG. 2 is a second perspective view thereof, illustrated in a second position;

FIG. 3 is a third perspective view thereof;

FIG. 4 is a front view thereof;

FIG. 5 is a back view thereof;

FIG. 6 is a left view thereof;

FIG. 7 is a right view thereof;

FIG. 8 is a top view thereof; and,

FIG. 9 is a bottom view thereof.

The broken lines in the drawings are for the purpose of illustrating portions of the stand for portable electronic devices that form no part of the claimed design.

1 Claim, 9 Drawing Sheets
